UNITED STATES PATENT OFFICE.

JOHN B. PLUM, OF NORTH YAKIMA, WASHINGTON.

BOILER.

1,172,043.

Specification of Letters Patent. Patented Feb. 15, 1916.

Application filed July 19, 1915. Serial No. 40,712.

To all whom it may concern:

Be it known that I, JOHN B. PLUM, a citizen of the United States, residing at North Yakima, in the county of Yakima and State of Washington, have invented 5 certain new and useful Improvements in Boilers, of which the following is a specification.

This invention relates to boilers or cookers such as are used for the canning and preserving of fruits and vegetables.

The object of the invention is to provide an improved construction of boiler which shall be more efficient and economical in 15 operation than those heretofore employed. To this end, I provide a boiler equipped with a bottom having inclined surfaces, by means of which the heating area is increased and the circulation of the water improved. 20 I also provide a boiler with smoke flues located adjacent the bottom and shaped to conform therewith.

In order that the invention may be readily understood, reference is had to the accompanying drawings, forming a part of this specification, and in which,

Figure 1 is a longitudinal section through the boiler or cooker constructed in accordance with my invention; Fig. 2 is a cross 30 section thereof; Fig. 3 is a sectional elevation taken substantially on the line 3—3 of Fig. 1, looking in the direction of the arrow; Fig. 4 is a cross sectional view similar to Fig. 2, showing a slightly modified form 35 of cooker; and, Fig. 5 is a similar view showing a still further modified construction.

Referring to the drawings in detail, my 40 improved cooker comprises a furnace having the side walls 1, supporting suitable grate bars 2, and terminating at its upper edge in a bead or flange 3. The firebox of the furnace has a rear wall 4, from which extends a horizontal flue 5. This flue is 45 provided with end and top walls 6 and 7, respectively, forming a conduit for conveying the products of combustion into the kettle flues hereinafter described. The rear end of the furnace is preferably supported 50 by means of a suitable leg or prop 8. Seated in the open top of the furnace is a kettle 9, having a top 10 which fits substantially steam-tight and is provided with a steam escape pipe 11. The bottom of this kettle 55 is of peculiar and novel construction. Along each side is provided a comparatively thin

pocket or trough 12. From the upper inner edge of each pocket extends an inclined wall 13, inwardly and downwardly to a point on a level with the bottom of the pockets 60 12. The lower edges of these inclined walls join a comparatively narrow horizontal bottom 14.

In the construction shown in Figs. 1 and 2, I provide a pair of smoke tubes which are indicated at 15 and 16. Each of these is formed with an inclined outer wall extending adjacent and parallel with the corresponding wall 13 of the bottom of the kettle, and forming between itself and such wall a comparatively thin sheet 17 of water. The bottoms of the flues 15 and 16 are parallel with the bottom 14 of the kettle and spaced therefrom a similar distance. The inner sides of the flues 15 and 16 are vertical and spaced apart so as to form a vertical column or sheet of water 18.

It will be noted that the upper sides, such as 15^a, of the flues 15 and 16 are flat and lie in the same plane, and on these flat surfaces rest the bottoms of the trays in which the fruit cans are placed. The water may extend only to the level indicated at *x* and the trays may be of any suitable construction. They are shown in dotted lines and indicated by the reference character *y*.

When assembled, the kettle and furnace are so related that the products of combustion, flowing through the conduit defined by the walls 5, 6, and 7, are delivered into 90 the rear ends of the flues 15 and 16, and passing forwardly through such flues, discharge into a smoke stack 19. It will thus be seen that the water in the pockets 12 and along the walls 13 and 14 is exposed to the 95 direct heat of the fire, while the water between and above the flues 15 and 16 is strongly heated by the passage of the hot gases and products of combustion through such flues.

100 The disposition of the inclined walls of the bottom and flues induces a violent circulation of the water. From the pockets 12 the water rises along the inside walls of such pockets, and steam bubbles are also 105 formed along these walls. The water also passes downwardly along the inclined walls 13 and upwardly through the space 18, and also upwardly along the lower inclined surfaces of the flues 15 and 16 opposite the 110 walls 13.

In order to drain the water from the kettle

when desired, I arrange a drain pipe 20, extending across the bottom of the kettle and connected to the three lowest points thereof as shown in Fig. 2. This drain pipe 5 is preferably provided with a stop cock 21.

In Fig. 4, I have shown a kettle constructed with but a single smoke flue 22. This has a flat top wall 22^a on which the trays rest, and inclined side walls similar to those 10 shown in Fig. 2. The circulation is generally similar, although probably not so efficient as in the form shown in Fig. 2.

While in the construction so far described, I have shown a kettle having bottom plates 15 and flue walls disposed in angular relation to each other, I have illustrated in Fig. 5 a kettle in which curved bottom plates and flue sheets are employed. The same water pockets 12 along the sides are preserved, 20 and two flues 23 and 24 are illustrated. These flues have semi-circular bottoms and flat tops 23^a upon which the trays rest. The side edges are preferably beveled off, as indicated at 24^a. The bottom of the kettle is 25 formed of two semi-cylindrical portions, conforming in shape with the bottoms of the flues 23 and 24, and spaced therefrom to form curved water sheets 25. These unite 30 at the center as shown at 26. It will be observed that in this construction also the water spaces are inclined so that circulation 35 of water takes place up and down the side walls thereof, the tendency being for the water to rise upwardly at 26 and flow thence outwardly and downwardly into the pockets 12.

From the above, it will be seen that in all three forms of kettle, I have provided inclined walls and flues which afford increased heating surface and which produce an efficient circulation, and it is thought that the many advantages of the invention will be readily understood without further discussion.

45 In some cases, especially in the small

units, it may be desirable to omit the return flues and use my improved boiler in connection with any ordinary stove or furnace. In such case, however, I retain the irregular bottom with the inclined surfaces 50 and reentrant angles and secure the resulting advantages of better circulation and increased heating surface.

What I claim is:

1. A boiler having a continuous bottom 55 depressed at its center, and sloping upwardly at each side, and a smoke flue having continuous side and bottom walls conforming with the shape of said bottom and spaced therefrom to provide a relatively thin 60 upwardly and outwardly inclined sheet of water of uniform thickness.

2. A boiler having a pocket extending along each outside wall, the bottom of said boiler having a portion intermediate said 65 pockets of substantially the same level as the lowest points of said pockets, and other portions sloping upwardly from said lowermost portion to the highest point of said pockets, and a flue in said boiler having 70 walls conforming with and spaced from said bottom.

3. A boiler having a smoke flue extending therethrough, said flue having a flat top wider than the bottom and adapted to support can holding trays, and inclined sides 75 so disposed as to cause water to circulate upwardly therealong, when the flue is heated.

4. A boiler having an extended bottom 80 surface formed of relatively high and low portions, with inclined portions connecting the same, thus presenting an irregular outline having reentrant acute angles, whereby the heating surface is increased, and means 85 for subjecting such irregular bottom to the action of heat.

In testimony whereof I have affixed my signature.

JOHN B. PLUM.
